Patented Aug. 10, 1915.

UNITED STATES PATENT OFFICE.

PHILIP BECKER, OF UTICA, NEW YORK.

SHOE-JACK.

1,149,327.

Specification of Letters Patent. Patented Aug. 10, 1915.

Application filed May 27, 1915. Serial No. 30,857.

To all whom it may concern:

Be it known that I, PHILIP BECKER, of Utica, in the county of Oneida and State of New York, have invented certain new and useful Improvements in Shoe-Jacks; and I do hereby declare that the following is a full, clear, and exact description thereof, which will enable others skilled in the art to which it appertains to make and use 10 the same, reference being had to the accompanying drawings, and to the reference-numerals marked thereon, which form part of this specification.

My present invention relates to shoe-jacks 15 such as are used by shoemakers and shoe-repair men to support the last in desired position.

The object of my invention is to provide a shoe-jack that is simple in construction 20 and efficient in operation and readily adapted to be used under varying conditions for a great variety of work.

A further object of my invention is to provide a device of the class described that 25 will securely hold the last in position and that will readily admit of the last being detached from the jack and replaced thereon or replaced with another last.

A still further purpose of my invention is 30 to provide a shoe-jack that will hold the last in such a manner that a shoe may be readily placed upon the last and removed about thereon or entirely removed therefrom without interfering with the grip of the jack upon the last and without any part of the 35 jack coming into contact with the shoe and without any part of the shoe having to rest upon the jack.

A further purpose of my invention is to 40 provide a shoe-jack that may be moved about into any position without relaxing its hold upon the last and which may be operated to grip or release the last in any position when so desired.

45 Further objects and advantages of my invention will appear from the description of the device hereafter given and the claims thereupon made.

Figure 1 is a side elevation of a shoe-jack embodying my invention. Fig. 2 is a 50 sectional view on an enlarged scale on line 2-2 of Fig. 1. Fig. 3 is a view on an enlarged scale of a last such as is used with my jack, showing the upper side of the last

or the side away from the sole of the last. 55 Fig. 4 is a vertical sectional view on an enlarged scale of the upper end of the last supporting arm and its contained parts, and also the adjacent portion of the last.

Referring to the drawings in a more particular description, there is shown a strong upright 5 secured in any desired place as against a bench (not shown) upon which upright is provided a strong clamp 6 operated by winged nut 7 so as to pivotally hold 60 on a horizontal axis the bracket 8, the outer end of which 8^a when the said bracket is in its usual lowered position over-hangs a rigid element such as offset 5^a on the upright 5. In the bracket 8 is rotatably mounted 65 with its axis at right angles to the axis of the pivotal clamp 6, the depending shank 9 of jack base 10 supported above the outer end of said bracket. The said base is provided with an upwardly extending arm 12 70 and a beak 11 extending outwardly from the base and at an angle, preferably slightly less than a right angle, to said arm 12. Interposed between the bottom of the base 10 and the adjacent portion of the bracket 8 75 there will preferably be placed a washer or cushion 13 of leather or similar sound-deadening material. The base is secured to the bracket by suitable means engaging the end of the shank 9 projecting from its bearing 80 in said bracket 8 as by means of nut 14 and lock nut 15 engaging the threaded extended end of said shank 9, a washer 16 being interposed between nut 14 and the adjacent 85 surface of bracket 8. When the bracket 8 90 and the shoe-jack is in its usual lowered position as shown in Fig. 1 the end of shank 9 and the lock nut 15 will rest against the extended portion 5^a of the base thus affording a solid support directly beneath the shoe-jack. 95

Removably supported by the upper end of the upstanding arm 12 is last 17 through the upper or ankle surface 18 of said last being placed directly over the upper end 100 of said arm 12, preferably with a washer or packing 19 or similar sound-deadening material interposed therebetween. Extending into the last from the said ankle surface 18 is a hole 20 into which removably fits the 105 upper end of pin 21 which projects upward from the upper end of arm 12 and which is operatively connected to yielding or spring-

tensioned means tensioned to force the upper end of said pin 21 radially of the upper end of said arm 12 in about the direction in which the beak 11 extends from the base
5 10. Convenient means for so yieldingly forcing said pin 21 in the direction desired may consist of spring 22 located in the chamber 23 in which the pin 21 is swingingly or movably mounted on pivot 24 in
10 the upper end of arm 12 and interposed between the pin 21 and one of the walls of said chamber 23 so as to force the upper end of said arm in the said direction but admit of the arm being retracted upon sufficient force
15 being used to allow the last to be locked upon the shoe-jack as hereinbefore described. The instep of the last 17 on its side away from the sole is provided with a recess having reentering sides or a dovetailed mortise
20 33 formed by over-hanging sides 34 and with its end toward the toe of the last open. Into this open end mortise is adapted to be placed the oppositely-shaped or tenon end 25 of brace 26 which extends diagonally
25 downward and away from arm 12 and has its lower end slidingly and removably but non-rotatably fitted upon beak 11 by means of a hole 27 in the lower end of said brace fitting upon said beak, said beak in cross section
30 and said hole 27 being similarly shaped as by being rectangular so as to hold the brace 26 from any rotating motion upon the beak.
The operation of my shoe-jack is as follows: The operator places the last 17 of the
35 desired size with its sole upward upon the jack by fitting the hole 20 over the upwardly projecting pin 21 on upstanding arm 12 and with the open ended mortise 33 above the beak 11. The brace 26 is mounted
40 upon the beak 11 and slid inwardly thereon and its tenon 25 inserted in the mortise 33. Then by reason of the yieldingly tensioned pin 21 and the diagonal arrangement of
45 brace 26, the parts may be clamped or locked together so as to hold the last upon the top of the shoe jack until it is purposely removed therefrom. This locking together is effected through the pin 21 urging the last forward or to the right as the parts are
50 shown in Fig. 1 and keeps the heel of the last from being moved from its position above arm 12 while the mortise and tenon connection between brace 26 and last 17 prevents the last from being removed by upward motion thereof, and the diagonal arrangement of brace 26 coöoperating with pin 21 keeps the brace 26 from becoming disengaged from the last 17. The tendency of
55 pin 21 to move to the right as indicated in Fig. 1 also cramps or tends to swing the upper end of arm 26 to the right and thus takes up any slight looseness there may be in the mortise and tenon joint at the top of said brace or its sliding connection with the beak at the lower end of the brace and

thus holds the last rigidly in place without any looseness in the joints of said jack or its connection with said last. It will be seen that with the last so locked to the jack the last and jack may be swung about to any angle upon its clamp 6 which holds the bracket 8 to the upright 5 and without in any way affecting the rigidity of the locking engagement effected between the jack and the last. Similarly it will be seen that the last may be turned about in any direction upon the shank 9 journaled in its bearing in bracket 8 without disengaging the last. The last may be disengaged from the jack by temporarily overcoming the tension of spring 22 which is conveniently effected by forcing the last rearwardly which loosens the engagement of the parts sufficiently to allow of the brace 26 being moved outwardly on beak 11 and outwardly from the open ended mortise 33 until the tenon is removed from the mortise whereupon the last may be removed by moving it upward off of pin 21. The last may be again replaced on the jack or another last of similar or different size but having similarly arranged hole 20 and open ended mortise 33 may be placed on the jack by following the direction above outlined in detail, it being understood that the same brace 26 fits all sizes of lasts.

As the parts of the jack directly connected to the last are connected to the last upon its upper or ankle side away from the heel and at the upper side of the instep it will be obvious that a shoe may be readily placed upon the last or removed from the last without detaching the last from the jack or changing its position upon the jack. Moreover, it will be seen that at no time does any part of the upper of the shoe come into contact with the jack nor does any part of the shoe upper have to rest upon any part of the jack nor stand any of the strain of holding the last in place on the jack nor strain of contact of holding the shoe upon the jack. Again it will be noted that a jack constructed according to my invention will be operative both to hold the last in place or to have the last placed in position or removed therefrom without regard to the angle or position in which the jack may be or may be moved to. It will be understood that while the pivotal mounting of the jack base 10 upon the bracket 8 and the pivotal mounting of that bracket in clamp 6 is convenient and desirable such pivotal connections are not essential to my invention.

Whenever it is desired to fasten a shoe upon the last 17 in addition to the fit of the shoe upon the last, a strap may be placed about said shoe and passed downwardly through a slot 28 provided in the base or other convenient part of the jack. There is no possibility of the last becoming loose

no matter in what position the jack may be placed nor is there any possibility of the last being drawn upward from the jack when the shoemaker attempts to draw an awl up from a shoe upon the last. As soon as the last is adjusted in operative position upon the jack the shoemaker has the full use of both his hands for working upon the shoe. It will thus be seen that I have provided a shoe-jack which positively locks the last to the jack in a firm manner and yet which allows the last to be very readily removed when desired from the jack.

If it is desired to place the last upon the jack with the shoe already upon the last or to remove the last from the jack with the shoe still upon the last this may readily be done with most sizes and styles of shoes since the position of the upper end of brace 26 just before it is inserted in the mortise or after it is removed from the mortise is still close enough to the instep of the base to ordinarily prevent the shoe upper interfering with the necessary movement of the brace 26.

It is practically impossible to loosen the last from the shoe-jack as already described and, in fact, further working upon the last tends to tighten the grip of the jack upon the last. To obviate any possible dislocation of the parts by unusual movements or by heavy continued hammering upon the toe part of the last, a thumb screw 29 may be provided mounted in the main part of the brace 26 and extending therethrough into engagement with the beak 11. Setting this screw against beak 11 renders the last non-detachably attached to the jack either purposely or accidentally until the thumbscrew 40 has been loosened.

What I claim as new and desire to secure by Letters Patent is:

1. In a shoe-jack the combination of a base having a beak extending therefrom, oppositely placed on the base an upwardly extending arm, and upwardly extending brace secured to said beak, a last detachably secured to the upper end of said arm and of said brace, and yielding means tensioned to force said last toward said beak whereby said last is locked to said arm and said brace.

2. In a shoe-jack the combination of a base having a beak extending therefrom, oppositely placed on the base an upwardly extending arm, an upwardly extending brace secured to said beak and slanting toward the upper end of said arm, a last detachably secured to the upper end of said arm and of said brace and yielding means tensioned to force said last toward said brace whereby said last is locked to said arm and said brace.

3. In a shoe-jack the combination of a rigid elbow with an upwardly extending

arm and a beak at an angle thereto, an upwardly extending brace secured to said beak, a last detachably secured to the upper ends of said upstanding arm and said brace and yielding means tensioned to force said last and said brace together whereby said last is locked to said arm and brace.

4. In a shoe-jack the combination of a rigid elbow with an upwardly extending arm and a beak at an angle thereto, an upwardly extending brace secured to said beak and slanting toward the upper end of said upstanding arm, a last detachably secured to the upper ends of said upstanding arm and said brace and yielding means tensioned to force said last and brace together whereby said last is locked to said arm and brace.

5. In a shoe-jack the combination of a rigid elbow with an upwardly extending arm and a beak at an angle thereto, an upwardly extending brace secured to said beak and slanting toward the upper end of said upstanding arm, a last having its heel portion resting on said upstanding arm and having its instep portion detachably secured to the upper end of said brace, and yielding means engaging the heel portion of said last and the upper end of said arm and tensioned to force said last toward said brace whereby said last is locked to said arm and said brace.

6. In a shoe-jack the combination of a rigid elbow with an upwardly extending arm and a beak at an angle thereto, an upwardly extending brace secured to said beak and slanting toward the upper end of said upstanding arm, a last having its heel portion resting on said upstanding arm and having its instep portion detachably secured to the upper end of said brace, a movably mounted pin projecting from the top of said arm and engaging the heel portion of said last and yielding means tensioned to force said pin and therewith said last toward said brace whereby said last is locked to said brace and said arm.

7. The combination in a shoe-jack of a base having an arm and a beak projecting from said base at an angle to each other, a last detachably mounted on said arm at a predetermined angle, and a brace slidingly mounted on said last and on said beak and adapted to draw said last down onto said arm and said brace.

8. The combination in a shoe-jack of a base having an arm and a beak projecting from said base at an angle to each other, a last detachably mounted on said arm at a predetermined angle, and a brace movably secured to said beak and slidingly engaging said last whereby said last is detachably locked to the upper end of said arm and of said brace.

9. The combination of a shoe-jack having a base, an arm rigidly projecting therefrom,

- a last detachably mounted on said arm at a predetermined angle, and a brace having its upper end movable toward and from said arm and engaging said last whereby
6 movement of said brace toward said arm detachably locks said last to said arm and said brace.

Copies of this patent may be obtained for five cents each, by addressing the "Commissioner of Patents.
Washington, D. C."

In witness whereof I have affixed my signature, in the presence of two witnesses, this 20th day of May 1915.

PHILIP BECKER.
